United States Patent Office

Des. 187,532
Patented Mar. 29, 1960

187,532

CONTROL KNOB

Gerald V. Jakeway, Grand Rapids, Mich., assignor to
Keeler Brass Company, Grand Rapids, Mich.

Application July 6, 1959, Serial No. 56,671

Term of patent 14 years

(Cl. D26—13)

Fig. 1.

Fig. 2.

Fig. 3.

Fig. 4.

Fig. 1 is a perspective view of a control knob, showing my new design;

Fig. 2 is a top plan view;

Fig. 3 is a side elevational view of the side opposite that shown in Fig. 1; and

Fig. 4 is an end elevational view, the opposite end being a mirror image thereof.

I claim:

The ornamental design for a control knob, as shown and described.
